UNITED STATES PATENT OFFICE

STEPHEN C. RADFORD, OF OSHKOSH, WISCONSIN

DESIGN FOR A DISH OR SIMILAR ARTICLE

Application filed January 7, 1933. Serial No. 46,749. Term of patent 14 years.

To all whom it may concern:

Be it known that I, STEPHEN C. RADFORD, a citizen of the United States, residing at Oshkosh, in the county of Winnebago and State of Wisconsin, have invented a new, original, and ornamental Design for a Dish or Similar Article, of which the following is a description, reference being had to the accompanying drawing forming part thereof. In the drawing, Fig. 1 is a plan view of the dish showing my new design; and Fig.

2 is a side view thereof on a reduced scale.

The dominant feature of the present invention resides in the surface ornamentation, and the shape of the dish and the material of which it is formed are immaterial.

I claim:

The ornamental design for a dish or similar article, substantially as shown and described.

STEPHEN C. RADFORD,
